UNITED STATES PATENT OFFICE

WILLIAM H. JOHNSEN, OF DALLAS, TEXAS

DESIGN FOR A RADIATOR ORNAMENT

Application filed January 17, 1931. Serial No. 38,349. Term of patent 7 years.

To all whom it may concern:

Be it known that I, WILLIAM H. JOHNSEN, a citizen of the United States of America, and resident of the city of Dallas, county of Dallas, and State of Texas, have invented a new, original, and ornamental Design for a Radiator Ornament, of which the following is a specification, reference being had to the

accompanying drawings, forming a part thereof.

Fig. 1 is a plan view; Fig. 2 a side view, and Fig. 3 an end view of a radiator ornament showing my new design.

I claim:

The ornamental design for a radiator ornament, as shown.

WILLIAM H. JOHNSEN.
